(57) **CLAIM**

The ornamental design for a capsulorhexis guide as shown and described.

DESCRIPTION

FIG. 1 is a top perspective view of a capsulorhexis guide showing our new design;

FIG. 2 is a bottom perspective view of the capsulorhexis guide of FIG. 1;

FIG. 3 is a top view of the capsulorhexis guide of FIG. 1; FIG. 4 is a bottom view of the capsulorhexis guide of FIG. 1;

FIG. 5 is a front side view of the capsulorhexis guide of FIG. 1;

FIG. 6 is a rear side view of the capsulorhexis guide of FIG. 1;

FIG. 7 is a right side view of the capsulorhexis guide of FIG. 1; and,

FIG. 8 is a left side view of the capsulorhexis guide of FIG. 1.

The broken lines illustrate portions of the capsulorhexis guide that form no part of the claimed design.

1 Claim, 6 Drawing Sheets
